Primary Examiner — Kelley Donnelly(74) *Attorney, Agent, or Firm* — Wood Herron & Evans LLP(57) **CLAIM**

The ornamental design for a sample rack, as shown and described.

DESCRIPTION

FIG. 1 is a front isometric view of a sample rack showing my new design;

FIG. 2 is a rear isometric view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a cross-sectional view taken along line 7-7 of FIG.

5.

Left side elevational view is a mirror image of FIG. 6.

The portions of the sample rack depicted in broken dash lines represent the bounds of the claim and form no part of the claimed design. Neither the lines themselves, nor the region within said lines, form any part of the claimed design.
